UNITED STATES PATENT OFFICE.

WILLIAM E. PHILIPS, OF CLEVELAND, OHIO, ASSIGNOR TO THE STEARNS CONVEYOR COMPANY, OF CLEVELAND, OHIO, A CORPORATION OF OHIO.

PIVOTED BUCKET CONVEYER.

Application filed August 29, 1921. Serial No. 496,318.

To all whom it may concern:

Be it known that I, WILLIAM E. PHILIPS, a citizen of the United States, residing at Cleveland, in the county of Cuyahoga and 5 State of Ohio, have invented a certain new and useful Improvement in Pivoted Bucket Conveyers, of which the following is a full, clear, and exact description, reference being had to the accompanying drawings.

10 This invention relates to conveyers of the type adapted to transport coal or other materials and is particularly concerned with improvements in link conveyers wherein dumping buckets are employed.

15 The general object of the invention is the provision of a chain conveyer having simple and effective link joints in which the joints are provided with a novel bearing arrangement.

20 More specifically, my invention is concerned with the provision of a chain wherein certain links are arranged to pivotally and removably support buckets on a member which is demountable.

25 A further object of the invention is to provide a reinforcement member associated with extensions on the links; the axles of the buckets being supported on the extensions out of alignment with the link joints.

30 An additional object of the invention is to provide simple means in a pivoted bucket conveyer adapted to cause a distribution of the forces due to the weight of the load and the bucket.

35 Further objects will become apparent in the following description taken in connection with the accompanying drawings wherein Fig. 1 is a side elevation of a conveyer chain and buckets, showing the position of the parts when passing over a sprocket wheel; Fig. 2 is a plan of a conveyer embodying the features of my invention; Fig. 3 is an enlarged sectional elevation of a supporting roll and its associated 40 link; Fig. 4 is a cross-sectional view partly in plan, through the link and a supporting roll.

In constructing bucket conveyers it has been the general practice to pivotally mount the bucket on an axle which projected a considerable distance from the sides of the

bucket and which also served as a pivot pin for connecting the inner and outer conveyer links. In using this construction, however, special arrangement had to be made, where 55 the path of the conveyer was changed by passing over sprockets to obtain proper clearance between the buckets and the sprockets.

In other constructions suitable clearance was obtained by employing a pivot shaft similar to a crank shaft wherein the bucket was mounted on an offset portion of the shaft. This necessitated special mountings or special bearings on the bucket. This arrangement also caused a greater portion of the load to be carried by the inner links of the conveyer chain thus in time causing a buckling of the links as the various parts 60 wore away.

To overcome the objections noted I have provided a simple reinforcing means for a conveyer chain by which it is possible to obtain particular advantages over those types of conveyers wherein the bucket is mounted 65 on the link pin and also to retain the advantages of the constructions wherein the bucket axis is offset from the link joint.

In Fig. 2 I have illustrated a conveyer 70 of the bucket type wherein I have arranged double link roller chains on each side of the buckets. These chains are composed of outer link plates 10 having at one end an offset portion extending a distance equal to width of the link bar, and an inner link plate 11 having an offset portion of the same 75 length. The ends of the bars opposite the offset ends are mounted on a sleeve member 12 having a length equal to the width of the chain intermediate of the link joints, while the offset ends of the links are mounted on a stud member 14 which is carried by the 80 sleeve 12. Suitable rollers 16 having projecting hubs 17 serve to maintain the links 85 in properly spaced relation.

The stud member 14 may have an upset end 15 adapted to limit its transverse movement while the inner end may have a suitable pin 21 secured in the end thereof which is adapted to maintain the stud in position.

100 The offset end of the inner link 11 may have a parallel portion 13 extending beyond

the pivot point upon which I prefer to rigidly mount a reinforcing member 18. The member 18 may be secured to the inner link by any convenient means, as for instance, 5 suitable rivets 19 and 20.

The particular function of this reinforcing member is to distribute the load exerted upon the extension 13 of the link to the stud 14 and to the outer links 10 and also to 10 provide a suitable bearing for demountable bucket supporting means. The reinforcing member may therefore be of sufficient length to extend past the pivotal axis of the links so that the stud member 14 may be secured 15 thereto. I thus obtain a load bearing contact on the inner end of the stud equal to the combined width of the inner link 11 and the reinforcing member; the stud being rigid with these members.

20 To prevent any turning of the stud I have provided a slotted projection 22 on the reinforcing member in which the retaining pin 21 may be positioned. A very advantageous feature of my invention is that the buckets 25 27 may be quickly and readily removed from the bucket supports.

To simplify the manufacturing of the bucket support I have arranged the body portion of the reinforcing member 18 in 30 the form of a U-shaped rib 25 surrounding an open recess 24, on the outer face of a plate portion with which the rib is integral. This recess extends a considerable length 35 along the extended portion of the inner link bar. The rib 25 may taper inwardly and merge in the stud engaging end of the reinforcing member.

The end of bucket shaft or support 26 40 may be mounted in this slot; the slot terminating in a ribbed semi-circular opening which serves as a bearing for the end of the shaft. To rigidly maintain the shaft end in a locked position I have provided a straight pin 29 which may pass through the ribs of 45 the reinforcing member and engage the end of the shaft along the surfaces of a groove formed therein, thus maintaining the bucket shaft in rigid relation with the reinforcing member and preventing any transverse shifting thereof.

50 It is quite evident that any individual bucket may be removed from the conveyer or remounted thereon by the removal or insertion of pins 29, which enables the removal of the shaft 26 from its bearing 28 on the bucket, it not being necessary to disconnect any other parts of the conveyer. It will also be noted that the stud 14, the link 11, the reinforcing member 18 and the bucket shaft 26 are all rigidly assembled.

The greatest deterioration in chain conveyers is caused by the rapid wearing away of the links, pivots and parts associated therewith due to the grinding action of grit and dust and expensive bearing con-

structions have been provided to overcome this destructive wear.

By providing efficient lubricating means I have found that the dirt and dust may be forced out of the link connections and that the wear is thereby greatly reduced. To lubricate the various parts I have mounted a suitable coupling nipple 30 on the outer end of the stud 14 which is associated with a passageway 31 formed in the 70 stud. A radial passageway 32 formed in the stud 14 and sleeve 12 provides communication to a lubrication chamber 33 formed in the roller 16, whence a high pressure gun connected to the nipple 30 may 75 force the grease or other lubricant into the chamber 30 and along the bearing surfaces of the sleeve 12 and roller 16. As the sleeve extends to the outer link bars, the lubricant may also be forced between the sleeve and stud and between the contacting surfaces of the links 11. Lubricant may likewise be forced outwardly to the contacting surfaces of the projecting roller hubs 17 and the inner 80 surfaces of the link bars 10 and 11. 90

From the foregoing description of my invention it is quite apparent that any one or a number of the buckets may be quickly removed from the conveyer or be remounted thereon, while by the same arrangement I have retained the advantages of a solid offset bucket shaft. In other words I have obtained a proper clearance between the sprockets and buckets and at the same time I have distributed the forces, exerted on the conveyer by the load, equally to all of the chain links. In obtaining these various desirable features I have decreased the cost of the construction as the manufacture of the constituent parts involves only the simplest production operations. The reinforcing member as well as the roller may be rough castings made with just sufficient accuracy to obtain ease in assembling. Furthermore, by incorporating lubricating means in the roller I not only insure the proper lubrication of the various contacting parts but also provide a very effective method for cleaning the pivotal connections between the chain links and the rollers. 100 105 110 115

Having thus described my invention, I claim:—

1. In a conveyer of the class described, the combination of a pair of inner links, a sleeve mounted therein, a pair of outer links overlapping the inner links and overlapping the ends of the sleeve, a pivot pin extending through the sleeve and through the outer links, an offset bucket supporting bracket secured to an extension of one of the outer links, said bracket having a longitudinally extending slot formed therein adaptable for the reception of an axle of a pivotally supported conveyer bucket and a pin spanning the slot, said pin being 120 125 130

adapted to engage a bucket axle and maintain the same in a bucket supporting position relative to said links.

2. In a conveyer of the class described, 5 the combination of inner and outer links arranged in pairs, a bracket member secured to one of the outer links the bracket having an elongated slot formed therein and the bracket being offset relative to said

link, whereby one end of the slot may be 10 opened while a wall at the other end may comprise a bearing for a pivot bucket axle, and means spanning the slot adapted to maintain such an axle in engagement with the end wall of the slot. 15

In testimony whereof, I hereunto affix my signature.

WILLIAM E. PHILIPS.
